UNITED STATES PATENT OFFICE

167,437

COMBINATION PIANO AND ORGAN OR SIMILAR ARTICLE

Jack Barofsky, Los Angeles, Calif.

Application December 26, 1951, Serial No. 17,833

Term of patent 14 years

(Cl. D56—9)

To all whom it may concern:

Be it known that I, Jack Barofsky, a citizen of the United States, residing at Los Angeles, in the county of Los Angeles and State of California, have invented a new, original, and ornamental Design for a Combination Piano and Organ or Similar Article, of which the following is a specification, reference being had to the accompanying drawings, forming part thereof.

Fig. 1 is a front perspective view of a combination piano and organ or similar article, with the doors to the seating portion open and the doors on the vertical illuminable portions in partly open position, showing my new design.

Fig. 2 is a front elevational view thereof with the doors to the seating portion open and those on the vertical illuminable portion closed.

The side opposite that shown in the drawings is the same as the side illustrated. The back is plain.

The dominant features of my design are shown in solid lines in the drawings.

I claim:

The ornamental design for a combination piano and organ or similar article, as shown and described.

JACK BAROFSKY.
